(57) **CLAIM**

The ornamental design for a cabinet, as shown and described.

DESCRIPTION

FIG. 1 is a front perspective view of a cabinet showing our new design;

FIG. 2 is a rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof;

FIG. 9 is a top, right side, front perspective view thereof, with a door open;

FIG. 10 is a bottom, left side, front perspective view thereof, with the door open; and,

FIG. 11 is a front view thereof, with the door open.

The broken lines illustrating portions of the cabinet form no part of the claimed design. The dot-dash lines define the bounds of the claimed design and form no part thereof.

1 Claim, 9 Drawing Sheets
